UNITED STATES PATENT OFFICE.

IWAN LYCHYJ, OF SAULT STE. MARIE, ONTARIO, CANADA.

ENGINE-DRIVEN AIR-COMPRESSOR.

1,343,270.

Specification of Letters Patent. Patented June 15, 1920.

Application filed October 29, 1919. Serial No. 334,287.

To all whom it may concern:

Be it known that I, IWAN LYCHYJ, a citizen of Ukrainia, residing at Sault Ste. Marie, Province of Ontario, and Dominion of Canada, have invented certain new and useful Improvements in Engine-Driven Air-Compressors, of which the following is a specification.

This invention relates to a power generating and storing apparatus, and to control valve mechanism therefor and it has for a general object to provide a simple and compact arrangement of balanced parts whereby air may be compressed and stored for use.

Other objects relate to the provision of a novel arrangement of air compressor operating means and of valve control devices.

For further comprehension of the invention, and of the objects and advantages thereof, reference will be had to the following description and accompanying drawings, and to the appended claims in which the various novel features of the invention are more particularly set forth.

Figure 1 of the drawings is a plan view of a power generating and storing apparatus constructed according to my invention.

Fig. 2 is a side elevation thereof.

Fig. 3 is a front elevation thereof.

Fig. 4 is a detail sectional view of one of the automatic check valves.

Fig. 5 is a horizontal section on the line 6—6 of Fig. 4.

Fig. 6 is a rear elevation of the apparatus.

As here shown the base frame of my improved apparatus comprises a series of longitudinal base members or beams 1, connected at opposite ends by the cross beams 2.

Mounted upon one end of this frame are a pair of engines 4 of an ordinary horizontal reciprocating type and adapted to receive their motive fluid through a branched pipe 5 which leads thereto. These engines are supported above the main frame by the subsidiary frames 6 and are provided with the usual cross head guides 7 and crossheads 8.

From the crossheads 8 connecting rods 9 lead to an inner pair of crank arms 10 of a sectional crank shaft 11 journaled in bearings 12 on standards 13 projecting from the beams 1. Crank shaft 11 is provided with an outer pair of crank arms 14 to which connect the upper ends of links 15 whose lower ends connect to a pair of rock-arms 16 fixed on a transverse rock shaft 17 journaled in brackets 18 on the beams 1.

Fixed to the ends of the rock shaft 17 are crank arms 19 connected by pitman rods 20 to other arms 21 rigid with cranks 22 journaled in brackets 23 on the beams 1. The 60 cranks 22 have connected thereto the lower ends of thrust links 24 which support upon their upper ends counterweights 25 guided in vertical guides 26. A pair of horizontal bars 27 which extend longitudinally of the 65 apparatus are fixed midway of their length to these counterweights and have inwardly projecting fingers 28 which operatively connect to the piston rods of a series of pairs of air compressors each consisting of an upper 70 cylinder 30 and a lower cylinder 31 whose pistons are operated and united by a common rod 32. These cylinders 30 and 31 are supported by means of yokes 33 which are secured to parts 34 projecting upwardly 75 from the base frame and in conjunction surround the cylinders.

Located between the air compressors and supported by the base frame is a tank 35 forming a storage reservoir for the compressed air and provided with a pressure indicating gage 36. From the air compressor, pipes 37 lead to the tank, back flow of air being prevented by valves such as illustrated in Fig. 5. These valves each comprise 80 valve disks 38 seating upwardly on a seat formed by an inwardly projecting annular flange 39 on the wall of a housing 40 mounted upon the tank, the valve disk being yieldingly led against its seat by coiled tension 85 springs 41 which connect at their lower ends thereto and at their upper ends to a spider 42 fixed upon a second inturned flange 43 on the housing, the pipes leading into the tops 90 of these housings. The cylinders 30 and 31 95 are provided with air intake ports controlled by one-way valves 44.

From a tank a pair of pipes 45 and 46 lead to a desired point, these pipes extending downward close to one another and are 100 provided with valves adapted to be controlled individually or in unison by a suitable valve mechanism.

In the operation of the apparatus as a whole it will be apparent that when a motive fluid is supplied to engines the pistons of the air compressors will be caused to operate by reason of the connections between the counterweights 25 and the piston rods 32, and between the thrust links 24, on 110 which the counterweights are supported, and the engines. The compressed air enters

the tank by depressing the valves 38 from their seats, back flow being prevented by the action of springs 41 as will be apparent.

Having thus described my invention what I claim as new and desire to protect by Letters Patent of the United States is as follows—

1. An apparatus of the type described comprising a base frame, a pair of engines 10 mounted on said frame, a plurality of air compressors arranged in two rows on opposite sides of the base frame and comprising upper and lower units operated by a common piston rod, vertically slidable weights 15 operatively connected to said piston rods, and means whereby said weights are lifted by said engines.

2. An apparatus of the type described comprising a base frame, a pair of engines 20 mounted on said frame, a plurality of air compressors arranged in two rows on opposite sides of the base frame and comprising upper and lower units operated by a common piston rod, vertically slidable weights 25 operatively connected to said piston rods, and means whereby said weights are lifted by said engines, said means including a pair

of thrust links upon the upper end of which said weights are supported.

3. An apparatus of the type described 30 comprising a base frame, a pair of engines mounted on said frame, a plurality of air compressors arranged in two rows on opposite sides of the base frame and comprising upper and lower units operated by a common piston rod, a storage tank located between the two rows of compressors, pipes leading from said compressors to said tank, and operative connections between said piston rods and said engines. 35

4. An apparatus of the type described comprising a base frame, an engine mounted thereon, a plurality of air compressors, and operative connections between said engine and said air compressors including a 40 vertically slidable weight, a rigid bar fixed to said weight midway between its ends, and a series of fingers projecting from said bar into engagement with the piston rods of the air compressors. 45

In testimony whereof I have affixed my signature.

I WAN LYCHYJ.
